UNITED STATES PATENT OFFICE.

ADOLPH BALLEMBERG, OF NEW YORK, N. Y.

SOCKET FOR CASTER-PINTLES.

1,177,675.

Specification of Letters Patent.

Patented Apr. 4, 1916.

Application filed December 17, 1915. Serial No. 67,355.

To all whom it may concern:

Be it known that I, ADOLPH BALLEMBERG, a citizen of the United States, and a resident of the city, county, and State of New York, have invented certain new and useful Improvements in Sockets for Caster-Pintles, of which the following is a specification.

This invention relates to the caster sockets placed in the legs of wooden furniture for the purpose of receiving, retaining and acting as a bearing for the pinte of the caster.

The primary object of this invention is to provide a simple, inexpensive but reliable socket of this type wherein the caster pinte will be securely retained within the socket, but allowed to rotate with a minimum amount of friction.

Another object of this invention is to provide a socket of this type in which the caster pinte is securely held and prevented from becoming dislodged and falling out when the article of furniture to which it is secured is lifted.

These and other objects are accomplished by my invention, a more particular description of which will appear below.

Reference is to be had to the accompanying drawings, forming part hereof, in which—

30 Figure 1 is a vertical sectional elevation of my improved socket with a caster pinte secured therein; and Fig. 2 is a side elevation of a portion of the socket.

Throughout the various views of the drawings, similar reference characters designate similar parts.

My improved caster socket consists of a tubular casing 1, the lower end of which is flanged at 2, and directly below this flanged portion 2 is a plate 3 preferably of hard, non-friction material as fiber, or the like, which plate is apertured at 4, so that the pinte 5 of the caster can pass through. The plate 3 and flange 2 are secured together by 45 a circumferentially flanged plate 6. Secured to the casing 1 and on top of the plate 6 is a plate 7 having an upturned edge 8, which is serrated at 9, these serrations extending into the leg of the furniture and 50 holding the casing securely in the leg after the casing has been driven therein.

The upper end of the casing 1 is flanged as at 10, and secured in the casing below said flanges is a plate 11. A flat spring is 55 also secured in the casing which spring has a pair of resilient side arms 12 in which are

depressed portions 13. The upper ends of the spring arms are connected by a cross piece 14 preferably formed integral with the arms, which cross piece is secured in 60 the casing 1, between the plate 11 and a plate or block 15 preferably of non-frictional material against which block the head 16^a of the pinte bears and rotates.

The sides of the casing 1 are apertured 65 as at 16 so that the arms 12 can spread outwardly and away from each other to allow the head 16^a of the pinte to pass the depressed portions 13 formed in the arms. After the head 16^a has passed these depressed portions and is in position as shown in Fig. 1, the spring arms 12 spring back to their normal position as shown in Fig. 1. The ends 17 of the spring arms 12 are splayed outwardly, as shown, and these 70 splayed portions enter apertures 18 in the casing to prevent interference with the head of the caster pinte when entering the casing.

Casings or sleeves of this character have 80 heretofore been made containing springs for the purpose above set forth, but have been so arranged that portions of the springs such as their ends extended outside of the plane of the casing, which prevented a removal of the casing unless great force was used, in which event the springs were broken or distorted and rendered useless. In applicant's construction it is to be noted that the spring at all times is contained within 85 the exterior limits of the casing so that the entire socket can be freely removed at any time without interference by the spring. It will also be noted that when the head 16^a of the caster pinte passes the depressions 13, 90 the ends 17 of the arms move inwardly and not outwardly, as has been the case with other articles of this type heretofore in use, wherein the ends generally were forced into the sides of the opening in the chair leg 95 rendering the spring inoperative.

From the foregoing, it will be noted that I have provided a caster pinte socket in which the pinte is securely held against dropping out, although the same may be 100 readily removed at any time desired by drawing on the pinte, the arms 12 expanding outwardly into the apertures 16 and allowing the head 16^a to pass the depressed portions 13.

From the foregoing, it is obvious that my invention is not restricted to the precise em-

bodiment shown, but is broad enough to cover all structures coming within the scope of the annexed claims.

Having described my invention, what I claim is:

- 5 1. A socket for caster pintles comprising a tubular casing, a spring having an arm secured in the casing adjacent its upper end, an inwardly extending projection formed in 10 the spring arm, a recess in the casing adjacent the projection, the extremity of the spring arm being so conformed in conjunction with the casing that lateral and outward movement of the same may be had 15 within the exterior limits of the casing.
  2. A socket for caster pintles comprising a tubular casing, a plurality of oppositely disposed spring arms in the casing, and a cross piece connecting them together adjacent 20 the upper end of the casing, inwardly extending projections formed in the spring arms, recesses in the casing adjacent the projections, the extremities of the spring arms being so conformed in conjunction 25 with the casing that lateral and outward movement of the same may be had within the exterior limits of the casing.
  3. A socket for caster pintles comprising a tubular casing, a spring having an arm secured within and adjacent the upper portion 30 of the casing, said spring arm having an inward projection and extending downward along the inner surface of the casing, a recess in the wall of the casing adjacent said projection for allowing outer and lateral movement of the projection, and a recess in the casing adjacent the end of 35 the spring arm for allowing lateral and outer movement of the spring arm end.
  4. A socket for caster pintles comprising a casing, a spring contained within said casing for holding a caster pintle, openings in the side walls of the casing for allowing an expansion or spread of the springs and 40 plates for holding the upper end of the spring within the casing.
  5. A socket for caster pintles comprising 45
- a casing, a spring contained within said casing for holding a caster pintle therein, openings in the side walls of the casings for allowing an expansion or spread of the 50 spring and a block of non-friction material secured in the head of the casing between the upper portion of the spring and the head of the caster pintle. 55
6. A socket for caster pintles comprising a casing, a spring contained therein, said spring having a pair of resilient side arms connected at their tops by a cross member, apertures in the sides of the casing for 60 allowing an expansion or spread of said spring arms, and a block of non-friction material secured in the head of the casing between the cross member of the spring arms and the head of the caster pintle. 65
7. A socket for caster pintles comprising a casing, a spring contained therein, said spring having a pair of resilient side arms connected at their tops by an integrally formed cross member, depressions in said 70 side arms for engaging a caster pintle below its head, openings in the side walls of the casing for allowing a spread or expansion of the resilient arms, and a block of non-friction material secured in the head of the 75 casing between the cross member of the spring arms and the head of the caster pintle and forming a bearing for said head.
8. A socket for caster pintles comprising a casing, a spring contained within the 80 casing and having a pair of resilient side arms, having depressions therein to engage a caster pintle below its head, openings in the side wall of the casing, one pair of openings for allowing an expansion or 85 spread of the arms, another pair of openings into which splayed ends of the arms extend, a cross member for the upper ends of the resilient arms and a block of non-frictional material secured in the head of said casing 90 and below said cross member.

Signed at the city, county and State of New York, this 16th day of December, 1915.

ADOLPH BALLENBERG.
